RUSSEL FRISBIE, OF CROMWELL, CONNECTICUT, ASSIGNOR TO J. AND E. STEVENS & CO., OF SAME PLACE.

Design No. 2,553, dated January 15, 1867.

DESIGN FOR A MATCH SAFE.

The Schedule referred to in these Letters Patent and making part of the same.

TO ALL WHOM IT MAY CONCERN:

Be it known that I, RUSSEL FRISBIE, of Cromwell, in the county of Middlesex, and State of Connecticut, have originated and designed a new Design or Pattern for a Match Safe, of which the following is a full, clear, and exact description, reference being had to the accompanying drawings, making a part of this specification.

The design consists of a half flower vase, made of any suitable material, resting on a shelf supported by brackets fastened to an open-work back.

What I claim as my invention, and desire to secure by Letters Patent, is—

The design or pattern for match safes herein set forth.
